POSTURE CHAIR OR SIMILAR ARTICLE

Pehr J. Anderson, St. Charles, Ill., assignor to All-Steel Equipment Inc., Aurora, Ill., a corporation of Illinois

Filed July 5, 1960, Ser. No. 61,242

Term of patent 14 years

(Cl. D15—1)

FIGURE 1 is a rear perspective view of a posture chair or similar article, showing my new design; FIGURE 2 is a front perspective view thereof; and

The dominant features of the design reside in the portions shown in full lines on the drawing and are particularly characterized by the high, upstanding hub structure in combination with the upwardly inclined leg structures and the narrow forked back rest support.

I claim:

The ornamental design for a posture chair or similar article, substantially as shown and described.
